The ornamental design for a brick, as shown and described.

DESCRIPTION

FIG. 1 is a perspective view of a brick;

FIG. 2 is a left elevation view of the brick;

FIG. 3 is a right elevation view of the brick;

FIG. 4 is a top plan view of the brick;

FIG. 5 is a bottom plan view of the brick;

FIG. 6 is a front elevation view of the brick; and,

FIG. 7 is a rear elevation view of the brick.

The elements and structures shown in dotted lines depict environmental subject matter and do not form part of the design.
